JIRO MATSUSAKI, OF ONOMICHI, KATOGUN, JAPAN

DEVICE FOR AUTOMATICALLY CHANGING PHONOGRAPHIC NEEDLES

Application filed February 27, 1931, Serial No. 518,816, and in Japan March 12, 1930.

My invention relates to a device for automatically changing phonographic needles of a phonographic machine in which a sound box is attached to and associated with the end of a sound tube consisting of two parts which are to be relatively rotated to bring the sound box retired from above the turn-table in order to permit the change of a record thereon.

10 One object of my invention is to provide means for automatically changing phonographic needles at each time when the record on the turn-table is changed.

Another object of my invention is to provide means which is compact and may be easily mounted on the sound box itself.

A further object of my invention is to obtain a device specified which is simple in construction, effective and positive in operation.

20 There are other objects and particularities of my invention which will be made clear in the following description with reference to the accompanying drawings wherein:—

Fig. 1 is a general plan view of one embodiment of my invention.

Fig. 2 is a back elevational view of the sound box shown in Fig. 1.

Fig. 3 shows a sectional elevation taken along line III—III in Fig. 2.

30 Fig. 4 is a sectional view taken along line IV—IV in Fig. 3.

Fig. 5 is a top end view of the combined needle gripper and guider shown in Figs. 2 to 4, inclusive.

35 Fig. 6 is a bottom end view of the same.

Fig. 7 is an extended view of the two members of needle gripper.

Fig. 8 is a view showing the needle changing or renewing operation of the device.

40 Fig. 9 is a perspective view of several parts of the needle reservoir.

Fig. 10 is a transverse sectional view of the body of needle reservoir.

45 Fig. 11 is an enlarged longitudinal sectional view of the mechanism for transmitting movement between the sound tube and the plunger.

Referring to the drawings, the device shown comprises, in general, a sound tube 1 consisting of two parts 2 and 3, and a sound

box 4 attached to and associated with the part 3 of the sound tube. The outer end of the part 2 is pivotally connected to and supported on a casing, not shown, of a phonographic machine and communicated with a sound-horn in the casing, while the part 3 is rotatably carried by the part 2 at the inner end, and communicates the part 2 with the diaphragm chamber of the sound box 4.

The part 2 is provided at the inner end with a bevel gear 5 therearound, which meshes with a second bevel gear 6 mounted on a shaft 7 carried by the part 3 by means of a suitable arm member 8 attached to the inner end portion of the part 3.

Within the sound box 4, an annular chamber 9 is formed between the outer wall 10, inner wall 11, side wall 12 and the wall of a horn member 13 which connects the diaphragm chamber 14 to the inside of part 3 of the sound tube.

A plunger 15 is disposed in the chamber 9 along a center line thereof, longitudinally movably, and guided by a member 16 fixed to the outer wall 10 and suitable perforations in the wall of the horn member 13. The plunger 15 is provided with a bent extension 17 having teeth 18 to form a rack bar, which meshes with a pinion 19 on a shaft 20 in the chamber 9.

The shaft 20 extends through the wall 10 and carries at the outer end a bevel gear 21 which meshes with a second bevel gear 22 mounted on a shaft 23 rotatably supported by a suitable arm member 24 attached to the adjacent end of the part 3. The shaft 23 is enlarged at the end portion opposite to the gear 22, and provided with a screw-threaded bore 25 formed therein. A screw member 26 cooperates with the threaded bore 25 and is provided with a head 27 having a cylindrical extension which is inserted into a corresponding hole or recess 28 of a connector 29 and fixed thereto by means of a screw 30.

The connector 29 has at the opposite end a hole 31 having a rectangular or square cross-section into which the corresponding rectangular or square end of the shaft 7 is slidably inserted. With the screw 30 released, the normal position or spacing of the head 27

with respect to the end of the shaft 23 may be adjusted by turning the screw member 26 in either direction. This adjusts the time at which the plunger 15 starts its outward movement, as hereinafter described.

- 5 On the outer or back wall 10 of the sound box, a needle reservoir 41 is detachably mounted. The reservoir comprises a body portion 42 provided with a longitudinal slot 43 of a spiral shape. The thickness of the body portion 42 is substantially equal to the length of the phonographic needle a , and the width of the slot is substantially equal to but slightly larger than the diameter of the 10 needle a . The slot 43 is closed at the bottom by a bottom plate 44 while at the top by a top cover 45.

The body 42 is provided at the center of the spiral with a circular bore 46, while the 20 plate 44 and cover 45 are respectively provided with a square bore 47 and 48, and a shaft member 49 passes through these bores in series. The shaft member has two short sections of a square cross-section and a long 25 main section therebetween of a circular cross-section. At the square short sections, the shaft member receives the top cover and bottom plate, respectively.

- The lower end of the shaft member 49 is 30 attached to the inner end of a spiral leaf spring 50, the outer end of which is attached to the wall of a cup-shaped cover 51 having a wide flange 52 suitably attached to the body 42. The cover plate 45 has formed therein at 35 the inner side a radial groove 53, while the bottom plate has formed therein a radial groove or slot 54 in one and the same vertical plane with the groove 53, and the ends of a pin 55 engages in these grooves, respectively. 40 The pin 55 has a diameter substantially equal to the needle a .

After the parts shown in Fig. 9 are assembled, they are held clamped by a screw 56 which cooperates with a screw threaded hole 45 formed in the end of the shaft member 49. The pin 55 is continuously biased towards the outer end of the spiral slot 43, by the spring 50 through the shaft member 49 and the plates 44 and 45, urging the phonographic 50 needles a stored within the slot 43 in side-by-side relation with one another as shown in Fig. 10 towards the outlet opening or feeding groove 57 which is in alignment with the plunger 15, the upper end portion of which is 55 normally inserted in the groove 57 to such a position that the upper end face of the plunger abuts the lower end of the needle a in the feeding groove 57.

- A combined needle guiding and gripping 60 device 60 is provided at the needle point of the sound box 4. The device comprises two cooperating members 61 and 62 forming a jaw hinged at the extensions 63 and 64 by means of a screw 65, and urged or biased to 65 each other by a spring 66 which is wound

around the screw 65 and held in position thereby, the ends of the spring acting on the outsides of two members 61 and 62, respectively.

The members 61 and 62 have symmetrical grooves 67 and 68, respectively formed in the inner sides. The grooves 67 cooperate to form a gripping groove 69 and the grooves 68 cooperate to form a guiding groove 70 which communicates with the gripping 75 groove.

The holes are so formed and co-related that the guiding hole 70 is in alignment with the feeding groove 57 of the needle reservoir, and when a newly fed needle is pushed into the guiding hole 70, it is guided thereby along a curved path towards the upper opening up to such time when the tip portion extends beyond the upper opening and the bottom end is completely within the hole 70, 85 and when such a position is reached, the pressure of the spring 66 causes the new needle to laterally slip on the sloping faces of the grooves 67 and 68 into the gripping hole 69 and firmly gripped therein for operation. 90 It will be understood that the old needle formerly gripped in the hole 69 was released therefrom when the newly fed needle was pushed into the hole 70 causing the member 61 and 62 to be separated from each other 95 by wedge action of the new needle against the pressure of spring 66, as shown in Fig. 8.

The released needle a' drops into the passage 80 formed within the annular chamber 9 by a curved rib 81 integral with the wall 10. At the lower end of the passage 80, the wall 10 is provided with a discharging hole 82 therethrough. The hole 82 registers with a corresponding hole 83 formed in the inner wall 84 of a discharge box 85.

The box 85 comprises a back or outer wall 87, the inner wall 84 and two side walls 88, to form a U-shaped circular chamber 86 which straddles the end portion of the part 3 of the sound tube and detachably supported 110 thereby. The two open ends of the chamber 86 are closed by side faces of the needle reservoir 41 when assembled.

The needle discharged into the chamber 86 drops to flow into the sections remote from the opening 83. The sections are formed by hairs 89 fastened to the casing at one end, on the inner sides of the chamber 86 and all extending in the same direction. The hairs are directed inward or opposite to the hole 83, and the needles are permitted to pass therethrough from the hole 83, but prevented from back flow towards the hole 83, thus assuring the holes 82 and 83 to be clear 125 and also preventing noises caused by to and fro movement of the needles within the discharge box. The outer wall 87 may be made of celluloid or other transparent material for a ready inspection.

It is to be understood that the combined 130

needle guider and gripper 60 is connected at its extensions 63 and 64 with the diaphragm 100 through a connecting member 101, and held in position at the needle point by suitable means in a hollow arm 102.

5 In operation, when a record on the turntable, not shown, of the phonographic machine including my device, has been performed and the part 3 of the sound tube is turned from the operating position shown by dotted lines in Fig. 1 towards the retired position shown by solid lines in Fig. 1, the bevel gear 6 is caused to revolve by cooperation with the gear 5. This rotation of the 10 gear 6 causes the revolution of the screw 26, and the latter enters into the threaded hole 25 until the head 27 engages the end of shaft 23. The parts are so proportioned that when the part 3 is rotated to such a position 15 that the head 27 engages the end of shaft 23, the needle gripper 60 reaches to a position in which the outer end thereof is directed upwards, and consequently even if the gripped needle is released, it does not drop outwards 20 but drops into the passage 80, as hereinbefore described.

After the above-mentioned position is reached, the rotation of shaft 7 is transmitted to the shaft 23 and consequently to the 25 shaft 20 and pinion 19, and the plunger 15 is moved outwards to enter into the feeding groove 57 pushing the new needle therein into the guide hole 70, and when the two members 61 and 62 are separated or open sufficiently 30 by this insertion of the new needle, the old needle in the gripping hole 69 is released and drops into the discharge box 85 through the passage 80. The new needle is further pushed into the hole 70, and then shifted into 35 the gripping hole 69, when the spring 66 pushes the members 61 and 62 to each other and causes firm gripping of the new needle.

40 Any longitudinal shifting, which would otherwise be caused by axial pressures thereon during the reproducing operation, may be prevented by a small inner projection 111 on the member 62, which engages the lower end of the gripped needle. The projection is associated with a hair spring 112 or other light 45 spring means which pushes the needle end to disengage from the projection 111 for allowing the dropping of the released needle. When the needle is gripped, the hair spring lies between the needle end and the side wall 50 of the member 62.

In the above manner, the needle is automatically changed within the time when the part 3 assumes the retired position. After a record is changed, the part 3 is returned to the operating position. During this operation, the shaft 7 is turned in the opposite direction, and the screw 26 retires from the bore 25. Thus it is obvious that no motion is transmitted to the shaft 20.

55 It is, however, necessary to have the

plunger 15 returned to the normal position shown. For this purpose, a spiral spring 115 is disposed in the annular chamber 9. The outer end of the spring 115 is fixed to the wall 10, while the inner end thereof is attached to 70 the shaft of a gear wheel 116 meshing with the pinion 19. When the pinion is rotated during the needle-renewing operation, the spring 115 is wound to store sufficient energy, and when the driving connection at the screw member 26 and threaded bore 25 is released as above stated, the spring 115 causes the plunger 15 to return to the normal position. This motion causes the opposite rotation of 75 the shaft 23, and the relative positions of the screw head 27 and the end of the shaft 23 are recovered to normal.

When the plunger has retired from the feeding groove 57, the pin 55 pushes the needles outwards, and a new needle is fed into 80 the groove 57. During this movement, the upper and lower plates 45 and 44 revolve in unison with the needles, and there is no opportunity for the needle-tips damaged by 85 relative movement between it and the plate 90 45.

The plate 45 may be made of glass or other transparent material for easy inspection of the needle contents in the reservoir. For 90 charging the empty reservoir with needles, the reservoir is removed from the sound box, and needles are conveniently inserted one after another through the opening 57.

It will be understood that after a needle is gripped in the gripper 60, it is entirely independent from the reservoir, and the latter does never interfere with the reproducing operation of the needle point.

I claim:

1. Apparatus for automatically changing 105 phonographic needles of a phonographic machine, comprising a sound box, a sound tube consisting of two parts one revoluble with reference to the other and to which the sound box is attached, a needle reservoir carried 110 by said sound box and having a feeding groove formed therein for receiving a single needle from the reservoir, a plunger longitudinally movable in said sound box, means actuated by the relative rotary movement of 115 said two parts of the sound tube to move said plunger to cause the latter to eject a needle from the reservoir and means associated with the sound box for gripping said needle.

2. Apparatus as claimed in claim 1, in which the means for gripping the needle comprises a pair of pivoted jaws movable toward and from each other and having a groove in their opposing sides to receive a needle from the plunger and a second groove for the final reception of said needle and cam surfaces at the outer end of the first named groove to direct the needle from said 125 first named groove into the second named 130

groove and a spring active to close said jaws.

3. Apparatus as claimed in claim 1, in which the means for gripping the needle comprises a pair of pivoted jaws movable toward and from each other and having a groove in their opposing sides to receive a needle from the plunger and a second groove for the final reception of said needle and cam surfaces at the outer end of the first named groove to direct the needle from said first named groove into the second named groove and a spring active to close said jaws and a second spring to cause disengagement of the needle from the jaws.

15 4. Apparatus as claimed in claim 1, including a discharge box carried by the sound box and arranged to receive needles released from the gripping means.

5. Apparatus as claimed in claim 1, including a discharge box carried by the sound box and arranged to receive needles released from the gripping means, said discharge box having hairs on its inner side arranged to prevent retrograde movement of the needles therein.

25 6. Apparatus as claimed in claim 1, in which the needle reservoir comprises a body having a slot therein corresponding in width and depth with the diameter and length of the needles and means resiliently urging the needles in said groove toward the feeding groove.

7. Apparatus as claimed in claim 1, in which the means for actuating the plunger comprises a gear fixed to one tube member, a gear in the sound box, a rack bar on the plunger engaging the last named gear, an intermediate shaft and gears connecting said intermediate shaft to the first and second named gears.

35 40 8. Apparatus as claimed in claim 1, in which the means for actuating the plunger comprises a gear fixed to one tube member, a gear in the sound box, a rack bar on the plunger engaging the last named gear, an intermediate shaft and gears connecting said intermediate shaft to the first and second named gears, said intermediate shaft having means to vary the length thereof for the purpose set forth.

50 In testimony whereof I affix my signature.

JIRO MATSUSAKI.
